Primary Examiner — Brett Miller*Assistant Examiner* — Jessica M Gebhart(74) Attorney, Agent, or Firm — Kearney, McWilliams & Davis, PLLC; William Yarbrough, III(57) CLAIM

The ornamental design for a tote bag, as shown and described.

DESCRIPTION

FIG. 1 is a front-side perspective view of a tote bag.

FIG. 2 is a front view of a tote bag of FIG. 1 thereof.

FIG. 3 is a rear view of a tote bag thereof.

FIG. 4 is a right-side view of a tote bag thereof.

FIG. 5 is a left-side view of a tote bag thereof.

FIG. 6 is a top view of a tote bag thereof; and,

FIG. 7 is a bottom view of a tote bag thereof.

The evenly spaced broken lines in the drawings depict stitching and are a part of claimed design.
